UNITED STATES PATENT OFFICE

148,888

DESIGN FOR AN EXPANSIBLE BRACELET

Franklin Stewart Rice, Cranston, R. I., assignor to Marvel Jewelry Mfg. Company, Providence,
R. I., a corporation of Rhode Island

Application February 12, 1947, Serial No. 136,859

Term of patent 7 years

(Cl. D45—4)

To all whom it may concern:

Be it known that Franklin Stewart Rice, a citizen of the United States, residing at Cranston, in the county of Providence and State of Rhode Island, has invented a new, original, and ornamental Design for Expansible Bracelets, of which the following is a specification, reference being had to the accompanying drawing, forming part thereof, wherein:

The dominant feature of my design resides in the portion shown in full lines.

I claim:

The ornamental design for an expansible bracelet, as shown and described.

FRANKLIN STEWART RICE.
